FIG. 1.

FIG. 2.

FIG. 3.

FIG. 4.

Inventor:

Harry S. Steen,
By *Christina, Wiley, Nancy, Harold, William,*
Settig S.

UNITED STATES PATENT OFFICE

2,212,308

FAUCET

Harry S. Steen, Chicago, Ill., assignor to Chicago
Faucet Company, Chicago, Ill., a corporation
of Illinois

Application July 13, 1939, Serial No. 234,320

1 Claim. (Cl. 251—138)

This invention relates to improvements in faucets and is here shown as applied to a self-closing faucet.

Among the features of my invention is the provision of a removable unit including a sleeve with means for preventing entrance of water (or other fluid being controlled) into the upper part of the sleeve. In a device of this kind, the removable sleeve contains a spring and other working parts; and it is desirable to keep these parts free from the fluid being passed through the faucet.

Another feature of my invention is the improved dash pot for checking the closing of the faucets.

Other features and advantages of my invention will appear more fully as I proceed with my specification.

In that form of device shown in the accompanying drawing—

Figure 1 is a vertical sectional view; Fig. 2 is a view taken as indicated by the line 2 of Fig. 1 on an enlarged scale; Fig. 3 is an enlarged vertical sectional view of the cap; and Fig. 4 is a bottom view thereof.

As shown in the drawing, 10 indicates a casing open at the top and provided with an inlet opening 11 at the bottom and an outlet opening 12 at one side. 13 indicates a sleeve in the casing with an inlet opening 14 at the lower end.

The lower end of this sleeve 13 carries a seat 15 (here shown as removable from the sleeve). The sleeve 13 is also provided with a plurality of outlet openings 16 discharging into the outlet 12 in the casing 10.

The top of the casing is closed by a cap 17. 13 indicates a vertically movable metallic stem extending through the sleeve. The lower end of this stem projects through the inlet opening 14 in the lower end of the sleeve 13 and carries a valve disc 19 adapted to seat upon the seat 15 to close the faucet when the vertically movable stem 18 reaches the upper limit of its movement. Downward movement of the stem 18 is adapted to remove the disc 19 from the seat 15 to open the faucet.

18^a indicates an extension of the stem 18 telescoped over the upper end thereof extending through a central hole in the cap 17 and provided at its upper end with an operating handle 20. The lower end of this member 18^a carries cam surfaces 21 cooperating with cam surfaces 22 in the cap 17 so that rotation of the member 18^a will lower the cams 21 to cause them to engage the collar 23 on the stem 18 to depress the same against the tension of the spiral spring

24. The cam surfaces on the cams 21, 22 are steep enough so that when the handle 20 is released, the spring 24 will force the stem 18 upwardly to close the faucet.

The lower end of the sleeve 13 above the port 16 is provided with an internal annular shoulder 25 above which is provided the packing 26, washer 27 and gland 28, the latter being engaged by the lower end of the spring 24. The packing 26 prevents water from entering the sleeve 13 above the shoulder 25 and thus protects the spring 24 and other working parts of the faucet from attack by the liquid being passed through the faucet.

The cap 17 is held in position tightly on the upper end of the casing 10 by means of the nut 29.

25 indicates a dash pot cylinder removable through the upper end of the casing 10 after the cap 17, sleeve 13 and stem 18 have been removed. Ordinarily, in removing these parts, the dash pot 20 cylinder will come up with them owing to the friction of the plunger therein. The cylinder 35 is provided with an outwardly projecting flange 35^a at its upper end adapted to be gripped between the upper portion 15^a of the seat 15 and the internal shoulder 10^a in the casing 10. In general terms it may be stated that the flange 35^a is gripped between the lower end of the sleeve 13 and the portion of the casing 10 (internal shoulder 10^a) surrounding the inlet opening 11. 30

Since the sleeve 13, as here shown, carries on its lower end a removable seat 15, it may be more accurate to state that the flange 35^a on the cylinder 35 is gripped between a portion of the removable seat 15 and a portion of the casing 10 35 surrounding the inlet opening 11. Since the upper part of the seat 15, however, does not function as a seat, it may broadly be considered as a part of the lower end of the sleeve 13 or the equivalent thereof. In constructions similar to 40 this, the lower end of the sleeve 13 may have a seat formed integral therewith. In such case, the flange 35^a would be gripped between the lower end of the sleeve (such lower end being integral with the sleeve) and a portion of the casing (internal shoulder 10^a) surrounding the inlet opening 11. In describing and claiming the invention, therefore, it is proper to state in broad terms that the flange 35^a is gripped between the lower end of the sleeve and a portion of the casing 45 surrounding the inlet 11.

The lower end of the stem 18 is provided with a piston or cup washer 36 operating in the cylinder 35. Above this piston, the cylinder 35 is 50 55

The lower end of the stem 18 is provided with a piston or cup washer 36 operating in the cylinder 35. Above this piston, the cylinder 35 is 55

provided with holes or inlet openings 35^b for the flow of water.

38 indicates a nut on the lower end of the stem 18 to hold the disc 19 and piston 36 thereon. 39 5 indicates a spacing member and 40, a washer.

Mounted in the lower end of the cylinder 35 is a spring 41 with its lower end 42 extending through the hole 43 in the bottom of the cylinder. As here shown, the cylinder is provided 10 with an extension 44 in which this hole is formed. The lower end of the wire 42 is flattened, as indicated by 45. The hole 43 is a port or bleed hole to permit the flow of water therethrough to permit vertical movement of the cup washer or 15 piston 36. The size of this hole will regulate the speed of closing of the faucet. Since this hole is ordinarily very small, there is danger of its becoming clogged up. I prevent this by inserting through the hole 43 the wire 42 which is 20 moved downwardly every time the stem 18 is lowered and which again is raised by the spring 41 when the faucet is closed. This movement of the wire 42 in the hole 43 keeps it clear and free of obstructions.

While I have shown and described certain embodiments of my invention, it is to be understood that it is capable of many modifications. Changes, therefore, in the construction and arrangement may be made without departing from 5 the spirit and scope of my invention as disclosed in the appended claim, in which it is my intention to claim all novelty inherent in my invention as broadly as permissible, in view of the prior art.

10 What I claim as new, and desire to secure by Letters Patent, is:

A faucet, including: a movable stem carrying a valve; a dash pot cylinder; a piston on the valve stem in the dash pot cylinder to retard closing 15 of the valve; a port in the cylinder; and a spiral spring in the cylinder, said spring having its upper end bent downwardly and extended through the port, said spring adapted to be engaged by the valve stem upon movement thereof, whereby 20 the port is kept free and clear of obstructions.

HARRY S. STEEN.
